STANLEY MILLIS, JR. ATTORNEY

UNITED STATES PATENT OFFICE

EUGENE KELLER, JR., OF WYOMING, OHIO, ASSIGNOR TO THE PHILIP CAREY MANUFACTURING COMPANY, A CORPORATION OF OHIO

PAVEMENT AND PAVEMENT MAT

Application filed July 5, 1929. Serial No. 375,912.

My invention relates to an improvement in pavements and is especially adapted to pavements between tracks, or rails, or other fixed construction.

5 By my invention I provide a pavement mat which consists of suitable supports to which is fixedly secured a traffic surface. These mats can be and preferably are assembled in a factory so as to secure proper assembly of 10 the parts, desired size and form so that they may be readily laid in place and properly fit the space they are to occupy. The mats are held in position by a few attaching devices so that they may be readily taken up for inspection 15 or repair to any portion of the construction below them and then relaid without damage to or breaking of the traffic surface or to the mats.

20 My invention is especially adapted for use in pavements between and adjacent to rails to form railroad crossings or other pavement in the vicinity of tracks.

In the accompanying drawing and the following description I have shown and referred 25 to my invention as applied to a railroad crossing, but I would have it understood that my paving mats may be used at many other places with equal advantage such as roadways generally, automobile runways and any location 30 where it is desirable to have a pavement not affected by temperature changes, vibration, sudden shocks or moisture or water.

In the drawing, Fig. 1 is a cross section 35 through a railroad crossing. Fig. 2 is a top view reduced in size of the two mats, between the rails in Fig. 1.

In the drawing, A, A are rails mounted on tie plates B and fixedly secured to the cross ties E by spikes C. D, D are paving 40 mats composed of foundation or supporting members F which may be of wood, metal, cement or any suitable material sufficiently rigid and having the desired strength to sustain the weights passing over the traffic surface without sag. I have found wood string- 45

ers satisfactory, although cement, metal or other stringers could be used for this purpose. When wood is used it may be, if desired, waterproofed by saturating it with a suitable water-proofing material or by coating it with a water-proofing material. The use of this water-proofing however while preferable is not essential to my invention. The foundation members F may be of any desired length depending upon the length of the finished mat. I have found it very satisfactory to make the mats in six, seven, eight, ten or twelve feet lengths; therefore, the foundation members would be of that length. The width of the foundation members would vary, depending upon the place where the mats were to be located and also depending upon whether or not the mat was to be used in a curved track in which event the foundation members F could all be curved to correspond to the arc of the track where they were to be used or the outside foundation members curved and the intermediate member straight with the spacing between the members filled in with wood strips or wedges. If desired the wood foundation members F could be curved by cutting them to the desired arc in the factory. These foundation members are fixedly secured together in any suitable way. I have shown in the drawing, 50 however, rods G which pass horizontally through the adjacent members F and are provided at their ends with suitable nuts H to hold the members F in fixed position with respect to each other. The two or more foundation members F having been fixedly secured together by the rods or bolts G, I then apply on the foundation members F, 55 slabs I, I. These traffic slabs I, I are composed of bituminous material, fibrous material and granular mineral materials such as sand, granular slate, etc., which have been thoroughly mixed to form a homogeneous mass and then moulded to the desired size and form under pressure so as to form a com-

pact rigid yet somewhat plastic traffic surface. The hardness or density of the slab I, may be regulated and controlled by the character of the bituminous material used or the 5 quantity of fibre, or the quantity of granular mineral used or the quantity and character of two or more of such materials. The greater the quantity of mineral in proportion to the bituminous material used the harder 10 the product will be; the higher the melting point of the bituminous material the harder the product will be; all of which will be thoroughly understood by anyone familiar with the manufacture of products using bituminous materials. While in the drawing I have shown the slabs I, I as two in number on each mat a single slab I may be used or more than two. I, however, prefer when 15 more than one slab I is used to have them arranged to break joint with the joint between adjacent supporting foundation members F so that there is no unbroken vertical joint through the mat. The traffic slabs I are fixed to the foundation members F by suitable 20 screws, bolts or nails J. If desired, before placing the slabs I on the foundation members F, the upper surface of the foundation members F may be coated with an asphaltic or similar coating K, thereby cementing the 25 surface slabs I to the foundation members F and water-proofing the joint between them. The longitudinal and lateral edges of the mats are preferably vertical and at right 30 angles to the opposite surfaces of the mat but if desired the adjacent sides of the mats 35 could be provided with a tongue and groove or ship lap construction so as to break the joints between them. The mats D, D constructed as above described are in practice 40 preferably mounted upon a foundation or support, particularly in railroad crossings and similar railroad work, such as railroad 45 ties E. The mats being of considerable length in proportion to their width extend over a number of the ties spanning the space 50 between them and forming a solid rigid pavement fixed to and supported entirely by the ties E.

When my mats are used in railroad construction such as shown in the drawing, I provide rail filler X and Y as shown, Y being on the outside of the rail and X being on the inside of the rail and of such cross sectional form so as to provide a flange way for the 55 flange of the car wheel. To assist in supporting the rail filler flange section X, I provide an angle iron L having a horizontal member which extends longitudinally of the rail and upon which the rail filler rests and a vertical member extending along the side of the rail filler X parallel to the web of the rail between the rail filler X and adjacent mats D. This vertical member of the angle iron L does not extend to the traffic surface. The space 60 between the top of the vertical member of the

angle iron L and the traffic surface of the pavement is filled with any suitable material M and I have found preformed expansion joints very satisfactory for the purpose. The angle irons L are attached to the foundation member F of the mat by screws or other suitable means. After the fillers X and Y, the mats and the filler members M are in place I insert between the two mats a filler N preferably a preformed filler of bituminous material or bituminous material containing fiber such as an expansion joint. After the mats have been placed with the fillers M and N so that there is no space between them, I fasten the mats by lag screws O to the ties E.

By reason of the irregular surfaces of the ties E it may in some cases be desirable to provide a shim P covering the surface of the ties so as to afford a solid support on the ties for the mats. These shims may be of any suitable material.

While my pavement mats are especially adapted for railroad work where they may be rested upon the ties, I would have it understood that these mats may be used without ties or similar supports in many places, such for instance as providing runways for automobiles where it is desirable to have either a continuous pavement form the runway, in which case the mats could be laid laterally of the runway, or in the event it was desired merely to provide separate runways under the wheels in which event the mats could be laid directly on the ground at predetermined distances so that they would afford proper parallel runways for the wheels.

While I have shown in the drawing wood ties E, metal ties or other ties could be used in which event my mats would be attached directly to the metal ties by any suitable means such as bolts.

I claim

1. A pavement unit consisting of a plurality of traffic surface members, a removable mat composed of a plurality of supporting members, a rod passing through said supporting members for holding said supporting members together and means for holding said traffic surface members fixed with relation to said supporting members.

2. In a pavement, foundation members, a pavement mat supported by a plurality of said foundation members, said pavement mat consisting of a traffic surface, a support for said traffic surface, means fixedly securing said support and said traffic surface together and means attaching said pavement mats to said foundation members.

3. In a pavement, foundation members, a pavement mat supported by a plurality of said foundation members, said pavement mat consisting of a traffic surface containing a bituminous and a fibrous material, a support for said traffic surface, means fixedly securing said support and said traffic surface together and

- means attaching said pavement mats to said foundation members.
4. In a pavement, foundation members, a pavement mat supported by a plurality of said foundation members, said pavement mat consisting of a traffic surface containing a bituminous and a fibrous material, a wood support for said traffic surface, means fixedly securing said support and said traffic surface together and means attaching said pavement mats to said foundation members.
5. In a pavement, ties, a rail attached to said ties, a rail filler in said rail adapted to fill the space against the web of the rail below the underside of the ball and above the base of the rail and extending outwardly from the web of the rail and means supporting said rail filler, said means being held in position by a plurality of ties.
6. In a pavement, a rail, ties supporting said rail, a rail filler in contact with said rail, a pavement mat adjacent to said rail filler, said paving mat composed of a rigid supporting member adapted to support said mat on a plurality of said ties and a traffic surface attached to said supporting member, said traffic surface containing a bituminous and fibrous material, compacted to form a relatively rigid, yet plastic slab, and means sealing the joint between said mat and said rail filler.
7. In a railway construction, a rail, ties supporting said rail, a rail filler in said rail, an angle iron supporting the opposite side of said rail filler on the ties.
8. A rail filler to contact with the web of the rail and having a portion extending upward from the rail, an angle iron adapted to support the outer portion on any suitable foundation.
9. A rail filler composed of suitable material having a portion adapted to contact with the web of the rail and a portion extending upward away from the rail, an angle iron in contact with said last mentioned portion adapted to support said rail filler on rail ties.
10. In a railway construction a rail, a pavement adjacent to the rail, a rail filler in said rail, an angle iron supporting the edge of said filler and means fixedly securing the angle iron to the adjacent pavement.
11. A removable pavement unit consisting of a rigid supporting base, a traffic surface containing a fibrous and bituminous material, and means passing through the traffic surface into the supporting base fixedly securing the traffic surface in place on the supporting base.
12. A pavement unit consisting of a rigid supporting member, a traffic surface containing a homogeneous mixture of bituminous, fibrous and granular mineral materials formed into a relatively rigid yet plastic compact slab, and means passing through
